United States Patent Office

Des. 213,458
Patented Mar. 4, 1969

213,458

CUP

Gerald Gulotta, New York, N.Y., assignor to Block China
Company, New York, N.Y., a partnership

Filed Feb. 28, 1968, Ser. No. 10,757

Term of patent 14 years

U.S. Cl. D44—9
Int. Cl. D7—01

FIG. 1

FIG. 3

FIG. 2

FIG. 5

The dominant features of the design are shown in full lines.

I claim:

The ornamental design for a cup, substantially as shown and described.
